UNITED STATES PATENT OFFICE.

EDWARD DE WITT MASON, OF BUFFALO, NEW YORK.

MOVABLE COAL-ELEVATOR.

SPECIFICATION forming part of Letters Patent No. 245,531, dated August 9, 1881.

Application filed June 20, 1881. (No model.)

To all whom it may concern:

Be it known that I, EDWARD DE WITT MASON, a citizen of the United States, residing at Buffalo, in the county of Erie and State of New York, have made certain Improvements 5 in Movable Coal-Elevators, of which the following is a specification.

This invention relates to a device to be used on coal-wharves or elsewhere for elevating and 10 delivering coal, &c., from piles into vessels, canal-boats, &c., to save hand-labor and wheeling in barrows, &c.; and the invention consists in the combination of parts for this purpose; also, in the construction of the elevator 15 bucket and a telescopic spout, all as hereinafter fully explained.

In the drawings, Figure 1 is a side elevation, showing one end of the truck with the derrick-frame thereon, supporting the elevating-leg, the hopper, and part of the conveyer attached at the other side. Fig. 2 is a perspective of a part of the conveyer and of the weigh-hopper; Fig. 3, perspective of the coal-bucket; and Fig. 4, side elevation, in section, of the telescopic spout.

A A represent a substantial frame-work or derrick on a truck, B, having wheels at both ends and sides to move the device either way on a track or ground.

30 At the top of one side of the frame A is attached an elevating frame or leg, C, carrying endless chains a a, having attached thereto a series of elevating-buckets, D D. The bucket-chains run over large pulleys b b' on roller-shafts, one at the top and the other at the bottom of the bucket-frame C, and around which the buckets run.

At the top of the derrick is a stationary hopper, E, which receives the coal from the buckets D as they run endlessly in the frame or leg C. This bucket-leg C is thrown out at a longer or shorter angle by merely swinging it out on the wheel at the bottom, and it is folded close to the side of the frame and truck A B by the 45 slots d, (one in each side of the bucket-frame,) through which the shaft of the pulley b goes. This slot allows the leg to be raised to a vertical position and closed against the side of the frame A, out of the way when the device 50 is being moved or is not in use.

The buckets are of metal, and of the shape shown in Fig. 3, having flat backs and curved fronts, and with a series of teeth or iron fingers, e e e, projecting from the shovel-edge of the bucket, as shown. These are to aid in 55 picking up the lumps of coal, &c., making the action more sure in loading each bucket. The teeth or fingers are either formed in the edge of the front part of the bucket or are attached thereto, and are formed of the projecting ends 60 of the binding or strengthening strips e', of metal, on the buckets, as shown in Fig. 3. These buckets need not necessarily be of sheet metal, but may be of iron open-work, if desired.

On the side of the derrick A, opposite to 65 the elevating-leg, is hooked or otherwise fastened a conveyer, G, partly shown at g, where it is attached to the frame just at the bottom of the hopper E. (See Fig. 1.) This conveyer is an open frame with raised sides h h, and with 70 rollers i i at top and bottom, around which an endless apron, k, runs, the apron operated by a pulley and belt, the latter running to the engine that operates the bucket-leg, said engine being generally set on the truck B at one end, but not 75 shown, nor the belts, as not being deemed necessary, in the accompanying drawings. On this apron k are fastened a series of rows of teeth, l l, to hold the coal on and carry it to the weigh-hopper H, into which it leads, one end of the 80 conveyer-frame being attached to the hopper, as shown. As soon as the hopper is filled to the amount set on the scale a door, m, is opened and the contents are dumped out.

When the coal is to be spouted directly into 85 a vessel the telescopic spout I is brought into use instead of the conveyer and weigh-hopper. It is made square, round, or otherwise, with sliding sections or joints, that allow it to be pulled out or closed to fit it to reach a greater or 90 less distance in spouting coal into hatchways of vessels.

The whole device is simple, inexpensive, and easily operated, besides being very effective.

I claim—

1. The combination, with a derrick, A, and truck B, of the stationary receiving-hopper E, attached to the top of the frame A, the bucket-frame C, made adjustable by the slots d d, and with the buckets D D e e thereon, the conveyer 100

G, having the apron *k* and teeth *l l*, and the weigh-hopper H, all arranged and operating conjointly, substantially as and for the purpose specified.

5 2. In connection with a coal-elevator leg, the buckets D D, constructed with flat backs, curved fronts, and the teeth *e e e* on the front edge, either formed in the shovel-edge or of the projecting ends of the straps *e' e' e'*, substantially as and for the purpose specified.

In witness whereof I have hereunto signed my name in the presence of two subscribing witnesses.

E. DE WITT MASON.
